SEALED PACKAGE

Walter K. Berthold, Rockville, Conn., assignor to
Hartford-Empire Company, Hartford, Conn., a
corporation of Delaware

Application May 21, 1943, Serial No. 487,893

4 Claims. (Cl. 215—40)

This invention relates to improvements in sealed packages, especially hermetically sealed glass containers.

An object of the invention is to provide a sealed package of the character described wherein a partial vacuum within the glass container is utilized to maintain a closure cap for the container pressed firmly against a sealing gasket which spaces the cap from the container while cooperating with the latter and with the cap to form an effective hermetic seal.

A further object of the invention is to provide a sealed package of the character described in which the cap not only is maintained by a partial vacuum within the container in position to act on an interposed gasket to provide a hermetic seal between the cap and the container but also serves to press the gasket firmly into good lateral contact with a side wall of the container.

A further object of the invention is to provide a hermetically sealed package of the character described wherein the hermetic seal is obtained in a novel manner by the use of a relatively thin sealing gasket.

A further object of the invention is to provide a sealed package of the character described wherein a sealing gasket of a suitable compressible, resilient material is employed to form a hermetic seal between the cap and the container under the influence of a partial vacuum within the container acting through the cap to exert a generally downward pressure on the gasket so as to press the gasket into good sealing contact at its upper and lower ends with vertically spaced surfaces on the container and cap, respectively.

A further object of the invention is to provide a hermetically sealed package of the character described wherein the sealing of the closure cap onto the container can be accomplished satisfactorily by following conventional home canning practice and without necessarily involving the use of special equipment not ordinarily available in the home.

Other objects and advantages of the invention hereinafter will be pointed out or will become apparent from the following description of illustrative examples of sealed packages of the invention, as illustrated in the accompanying drawing, in which:

Figure 1 is a fragmentary view, partly in vertical section and partly in elevation, showing the upper portion of a glass container and a closure cap therefor, together with a sealing gasket interposed between the cap and the container, the view showing the relative positions of these parts

at an early stage in the operation of forming a hermetic seal between the closure cap and the container;

Fig. 2 is a view similar to Fig. 1 but showing the relation of the parts at the time of completion of the sealing operation;

Fig. 3 is a fragmentary vertical sectional view showing a modified form of sealed package, including a gasket of less thickness than that used in effecting the hermetic seal of Fig. 2; and

Fig. 4 is a view similar to Fig. 3 but showing a still different form of sealed package, including a metallic closure for the container instead of the glass cap of each of the preceding views.

15 A sealed package embodying the invention may comprise a glass container of any suitable or preferred form, such as any one of the various well known forms of bottles, jars, tumblers, etc. Such a container may be a jar, such as that partially shown in each of the views of the drawing and designated 10 in Figs. 1, 2 and 3 and 110 in Fig. 4.

16 The glass jar 10 has its upper end portion reduced in diameter, as indicated at 11, as is usual, 25 thus providing an external shoulder 12 at the juncture of this reduced upper end portion or neck of the container and the larger body portion thereof. The container is provided with an opening 13 extending through its reduced upper end portion or neck, as also is usual.

26 The open upper end portion of the container 10 has been formed, according to the present invention, with an external annular downwardly and inwardly tapering or inclined gasket side 35 sealing surface 14 adjacent to the container mouth. The sealing surface 14 is merged at its lower end into an upwardly facing gasket-end sealing surface 15. The surface 15 may be the upper surface of an external flange or bead 16 40 on the container 10.

41 The sealing surface 14 is shown as being merged at its upper end into the upper end surface 17 of the container wall by a rounded corner surface 18. The juncture of the surface 14 45 with the upper end surface 17 may be effected by any other suitable connecting surface although a rounded corner surface is preferred. The side sealing surface 14 is shown as including a slight under-cut portion or downwardly facing ledge at 19. This is included in the jar for convenience of manufacture by the use of conventional molds and is not essential to the invention.

50 A glass closure cap suitable for application to the jar 10 is indicated at 20 in each of Figs. 1,

2 and 3. The cap 20 has a depending flange or skirt 21 which is shown as being of sufficient length to extend downwardly in encircling relation to the upper end portion of the jar nearly but not quite to the level of the shoulder 12 of the jar. The inner wall 22 of the skirt of the cap is of greater diameter than the outer diameter of any part of the encircled upper end portion of the jar so that an annular space 23 is provided between the skirt of the cap and the outer wall of the upper end portion of the jar. The inner surface 22 of the skirt of the cap is merged into the lower surface 24 of the head or cover portion of the cap by a corner surface 25 which preferably is rounded or arcuately curved in vertical section, substantially as shown.

A gasket for use in forming a hermetic seal between the cap 20 and the jar 10 preferably is a ring of rubber but may be made of any other suitable material. Such a gasket is indicated at 26 in Figs. 1 and 2.

The gasket 26 may be of rectangular shape in cross-section, when uncompressed and undistorted. It has a thickness less than the width of the narrowest part of the annular space 23 between the skirt of the cap and the side bearing surface 14 on the jar 10. The length of the gasket is greater than the distance from the gasket supporting and end sealing surface 15 to the level of the upper end surface 11 at the mouth of the jar. This length is substantially greater, preferably several times greater than the thickness of the gasket. The inner diameter of the gasket, when it is uncompressed and undistorted, preferably is approximately the same as the diameter of the relatively smaller lower end of the side sealing surface 14 and thus somewhat smaller than the diameter of the larger upper part of such sealing surface. The outer diameter of the gasket preferably is less than that of the inner diameter of the adjacent portion of the skirt of the cap 20. The relative dimensions of these parts may of course vary considerably from those shown in Fig. 1.

In forming a hermetic seal between the cap 20 and the jar 10 with the use of the gasket 26, the gasket may be placed on the side sealing surface 14 of the upper end portion of the container so as to be seated at its lower end on the upwardly facing surface 15. The particular gasket 26 will be stretched slightly where it encircles the larger upper part of the side surface 14 and consequently also will be somewhat enlarged at its projecting upper end portion. The food product or other substance that is to be packed in the container may be placed therein in a heated condition so as to create the desired partial vacuum in the container when such substance has cooled. The filling of the jar with a hot substance may be done after the gasket has been placed on the jar. The glass closure cap then may be dropped onto the projecting upper end portion of the gasket on the jar, to the position shown in Fig. 1. It will be noted that the initial contact between the cap and the gasket will be in effect a line contact at the outer upper corner of the gasket with the rounded inner corner surface 25 at the juncture of the skirt and cover portions of the cap. This aids formation of an air-tight sealing relation between the upper end of the gasket and the inner wall of the cap as the thin corner edge of the gasket will flex and adapt itself accurately to the exact contour of the overlying wall of the cap. Consequently, as the contents of the jar begin to cool, a partial vacuum may be set up

therewithin. This will cause a downward pressure on the cap so that the sealing contact between the upper end portion of the gasket and the inner wall of the cap will be intensified and made more firm. It of course will be understood that an externally applied additional downward force may be applied to the cap, as by placing a weight thereon, to aid the action of the partial vacuum in the container in forming the desired hermetic seal and in moving the cap to its applied position. The downward suction on the cap, created by the cooling of the contents of the jar, will move the cap downwardly from the position shown in Fig. 1 to the position shown in Fig. 2, if such downward movement has not already been effected by some externally applied downward force, as by the action of a weight on the cap. If the cap already has been moved down to its Fig. 2 position, the suction thereon will maintain it in this position until the partial vacuum in the jar has been relieved.

It will be noted that in moving downward from the position shown in Fig. 1 to the position shown in Fig. 2, the contact of the rounded inner corner surface 25 of the cap with the gasket will tend to bias the upper end portion of the gasket inwardly as the gasket is compressed. This will intensify and make more firm the lateral contact of the inner wall of the gasket with the upper part of the sealing surface 14 and will stabilize the position of the cap on the jar. It will be noted further that the gasket supporting and lower end sealing surface 15 is shown as being inclined slightly in a downward direction from the horizontal to coincide with the inclination from the horizontal of the lower end surface of the gasket when the latter has been stretched at its upper part by its contact with the upper end portion of the container. This is the construction preferred by me although it is not essential that the upwardly facing gasket supporting surface 15 be parallel with the plane of the lower end surface of the gasket before the latter has been thrust downwardly against such supporting surface. An air-tight seal between the lower end of the gasket and the surface 15 will be firmly established by the cap-impelled downward thrust of the gasket against such surface and will be maintained so long as the cap is held down in its applied position by the partial vacuum within the jar.

When it is desired to open the sealed package, it is only necessary to insert a suitable implement, not shown, between the shoulder 12 and the lower edge of the skirt of the cap and to pry the cap upwardly sufficiently to relieve the vacuum at the upper end of the gasket 26.

The modified form of sealed package shown in Fig. 3 includes a gasket 26 which is relatively thinner in relation to its length than the gasket 26 of the preferred form of sealed package. In the sealed package shown in Fig. 3, the contact of the upper end of the gasket with the inner wall of the cap 20 may have been with the under surface of the head or cover portion of the cap throughout the sealing operation instead of initially being only at its outer corner portion with a rounded inner corner surface of the cap. In this form of sealed package and in the method of producing it, there is more need for the application of a downwardly directed external force on the cap in order to assure the establishment of the partial vacuum in the cap as the contents thereof cool than in the case of the package shown in Fig. 2. Also, the downward movement of the cap to its fully applied position, which is that

shown in Fig. 3, will not press the gasket laterally against the side sealing surface 14 with as much force as is produced in the operation of forming the hermetic seal of the preferred sealed package, as heretofore described. Otherwise, the sealed package shown in Fig. 3 is substantially like that shown in Fig. 2 and is produced in substantially the same way.

The sealed package shown in Fig. 4 comprises a glass container 110 having an external annular sealing surface 114 formed on its upper end portion and an upwardly facing gasket supporting surface 115 at the lower end of the surface 114. A gasket 226 has been placed on the upper end portion of the container 110 around the sealing surface 114 so as to be seated at its lower end against the surface 115. This will maintain the gasket 226 in a slightly stretched condition at its upper part, including the end portion thereof which projects above the upper end surface 117 of the container wall. A closure cap made of light gauge metallic or other suitable material is designated 120 and includes a downwardly extending flange or skirt 121. The cap 120 preferably is formed so that the inner surface of the skirt is merged into the inner surface of the head or cover portion of the cap by a rounded or arcuately curved corner surface 125, substantially as in the case of the glass cap 20.

In forming the package shown in Fig. 4, the metallic cap 120 may be placed over the gasket so that the outer corner edge at the top of the latter will bear against the rounded inner corner surface 125 of the metallic cap. In order to assure the creation of the partial vacuum within the container as the contents thereof cool, an externally applied downward pressure on the cap 120 may be required, particularly in view of the relatively light weight of this cap alone. This may be done by placing any suitable object upon the cap. I prefer however to effect this result by the use of a hold-down cap 150 which has a downwardly extending skirt 151 adapted to fit over the flange or skirt 121 of the sealing cap. The skirt 151 may be formed to include a screw-threaded portion 152 adapted to be screwed onto an externally screw-threaded portion 153 of the glass container. Thus, the cap 150 may be screwed onto the container to force the cap 120 downwardly to the desired extent and to hold it down until the hermetic seal has been established by the cooling of the contents of the container. The cap 150 then may be removed and used in the capping and sealing of other containers like the container 110. Or, the cap 150 may be left on the jar 110 until it is desired to open the latter. When this is to be done, the cover 150 may be removed and the cap 120 then may be pried loose from the gasket.

It will be noted that each of the illustrative sealed packages shown in the drawing and hereinbefore described may be produced by conventional home canning procedure, without necessarily requiring the use of any special equipment. It of course will be understood that the sealed packages may be produced by commercial methods and by the use of capping and sealing instrumentalities not available in the home. Thus, the vacuum might be produced by the use of any suitable known machine for effecting vacuum-sealing of caps onto jars, including those which do not rely upon cooling of the contents of the container to create the vacuum required to hermetically seal the cap to the container.

Various changes in and modifications of the

illustrative examples of the invention shown in the drawing will readily occur to those skilled in the art and the invention therefore is not restricted to the details of these examples.

I claim:

1. A sealed package comprising a glass container having an upper end portion formed with a vertical opening therein, said upper end portion of the container having an external upwardly facing supporting surface formed thereon adjacent to but below the level of the upper end of the container and having an upwardly enlarging side sealing surface formed thereon between said upwardly facing supporting surface and the upper end of the container, a gasket of compressible, resilient material of substantially greater length than thickness and having an initially smaller inner diameter, when unstretched, than the diameter of the upper part of said side sealing surface, said gasket being disposed on said side sealing surface so that its lower end is seated on said supporting surface and its upper end portion projects in a slightly expanded condition above the upper end of the container, and a closure cap having a cover portion overlying the upper end of the container and a skirt extending downwardly over the gasket, said cap being seated adjacent to the juncture of its cover portion and skirt on the upper end of the gasket and acting, in response to a partial vacuum in the container, to exert a downward pressure end-wise on said gasket to provide a hermetic seal between said container and said cap, said gasket, when uncomressed, being of substantially less thickness than the width of the space between the upper end portion of the container and the surrounding skirt portion of the closure cap.
2. A sealed package comprising a glass container having an upper end portion formed with a vertical opening therein, said upper end portion having an external upwardly facing supporting surface formed thereon at a level adjacent to but spaced below that of the upper end of the container, a closure cap having a cover portion disposed in covering relation to the upper end of the container and having a skirt extending downwardly over the upper end portion of the container in spaced relation therewith, and a gasket of compressible, resilient material of substantially greater length than thickness seated at its upper end against the cover portion of the cap adjacent to the juncture of said cover portion and the skirt of the cap and seated at its lower end on said upwardly facing supporting surface on the container so as to be pressed by said cap, in response to a partial vacuum in the container, into hermetic sealing relation at each of its opposite ends with the surface in contact therewith and laterally at its upper end portion against the wall of the container adjacent to the upper end of the latter, the thickness of said gasket, when uncomressed, being substantially less than the width of the space between the upper end portion of the container and the surrounding skirt portion of the cap.
3. A sealed package comprising a glass container having an upper end portion with a vertical opening therein, said upper end portion having an external annular side sealing surface of downwardly decreasing size, said upper end portion of the container having an upwardly facing surface formed thereon at the lower end of said side sealing surface, a glass closure cap having a cover portion overlying the upper end of the container and having a skirt extending downwardly around the upper end portion of the container in spaced

concentric relation therewith and to a level below that of said upwardly facing supporting surface, and a sealing gasket stretched around said side sealing surface and seated at its lower end on said upwardly facing supporting surface and at its upper end against the lower surface of the cover portion of said closure cap adjacent to the juncture of the latter with the skirt of the cap, said gasket having a thickness substantially less than its length and less than the radial distance 10 between the skirt of the cap and said side sealing surface on the container, said cap being impelled continuously by a partial vacuum within the container to exert downward pressure against the upper end of the gasket to maintain the latter 15 compressed end-wise between said cap and said upwardly facing supporting surface on the container.

4. A sealed package comprising a glass container having an upper end portion formed with a vertical opening therein, said upper end portion having an external upwardly facing supporting surface formed thereon adjacent to but below the level of the upper end of the container, a closure cap having a cover portion and a skirt portion, the cover portion overlying the upper end of the container and the skirt portion extending down-

wardly over the upper end of the container in spaced concentric relation therewith, said cap having an arcuately curved inner corner surface at the juncture of its skirt and cover portions, 5 and an endless gasket of compressible, resilient material and of substantially greater length than thickness, said gasket being seated at its lower end on said upwardly facing supporting surface and extending in closely fitting contact with the upper end portion of the container and above the upper end of the latter so as to be seated at its upper end against the inner surface of the cap, the upper end of the gasket being in contact at its outer edge with said arcuately curved inner corner surface of the cap, said cap being under downward pressure resulting from a partial vacuum in the container so as to maintain said gasket pressed end-wise against said upwardly facing supporting surface and laterally inward at its upper end portion against the adjacent wall of the upper end portion of the container, the thickness of said gasket, when uncompressed, 20 being substantially less than the width of the space between the concentric upper end portion of the container and the surrounding skirt portion of the cap.

WALTER K. BERTHOLD.
